UNITED STATES PATENT OFFICE

153,517

DESIGN FOR A LUBRICATION CABINET OR THE LIKE

Charles W. Ginter, Bryan, Ohio, assignor to The
Aro Equipment Corporation, Bryan, Ohio, a
corporation of Ohio

Application March 31, 1947, Serial No. 138,074

Term of patent 7 years

(Cl. D52—2)

To all whom it may concern:

Be it known that I, Charles W. Ginter, a citizen of the United States and a resident of Bryan, in the county of Williams and State of Ohio, have invented a new, original, and ornamental Design for a Lubrication Cabinet or the like, of which the following is a specification, reference being had to the accompanying drawing, forming a part thereof.

Figure 1 is a perspective view of a lubrication cabinet, illustrating my new design;

Figure 2 is a top plan view of the lubrication cabinet; and

Figure 3 is a side view of the cabinet.

I claim:

The ornamental design for a lubrication cabinet or the like, substantially as shown.

CHARLES W. GINTER.
